UNITED STATES PATENT OFFICE.

GUY B. SMITH, OF NEW YORK, N. Y., ASSIGNOR TO OTIS ELEVATOR COMPANY, OF JERSEY CITY, NEW JERSEY, A CORPORATION OF NEW JERSEY.

PLUNGER-ELEVATOR.

1,185,256.

Specification of Letters Patent.

Patented May 30, 1916.

Application filed March 11, 1914. Serial No. 823,890.

To all whom it may concern:

Be it known that I, GUY B. SMITH, a citizen of the United States, residing in New York, in the county of New York and 5 State of New York, have invented a new and useful Improvement in Plunger-Elevators, of which the following is a specification.

My invention relates in general to plunger elevators, and is directed more particularly to means for guiding and lubricating the elevator plunger.

An object of my invention is the provision of one or more plunger followers or 10 traveling guides for the plunger which are automatically positioned by the movement of the car so as to support the plunger against lateral movement at proportionately equal distances on the portion of the plunger 20 extending from the cylinder.

A further object of the invention is the provision of a simple, practical and efficient plunger follower which may readily be removed from the plunger when desired and 25 which combines the dual function of lubricating the plunger and supporting the same against lateral movement.

Other objects of my invention will appear hereinafter, the novel combinations of elements being pointed out in the annexed 30 claims.

In the drawings, Figure 1 is a diagrammatic representation of a plunger hydraulic elevator containing an embodiment of 35 my invention; Fig. 2 is a modification; Fig. 3 is a side view of Fig. 2; Fig. 4 is a detail elevation view of the plunger follower; Fig. 5 is a plan view of Fig. 4; Fig. 6 is a sectional elevation view of the plunger follower 40 showing the lubricating device.

Like reference characters denote similar parts in all of the figures.

It is well known in the art to which my invention relates, that in many plunger elevators it is impossible to prevent the plunger working loose from the car, and also to maintain the cylinder stuffing box tight against leakage unless some means is used to prevent a buckling or swinging of the plunger. This is true particularly in the case of high rise elevators, when the length of plunger oftentimes exceeds 250 ft. and when the elevator is called upon to perform abnormal work, such as lifting a heavy safe.

Since the plunger is supported upon a column of incompressible fluid, and carries upon its upper end a load represented by the unbalanced weight of the car and its load together with the weight of the plunger itself, it is readily seen that the plunger 60 is at times subjected to a heavy compression stress. As the plunger is universally constructed of steel tubing of very moderate thickness, it possesses considerable flexibility and it is found that the resultant deflection of the plunger sets up a vibration therein which not only results in loose connections and a leaky stuffing box, but also tends to set up an objectionable swaying or see-saw motion of the car which is particularly noticeable when the latter is undergoing a change of speed or in making a landing.

My invention is adapted to obviate the above noted and other disadvantageous features inherent in a plunger elevator, as well as to maintain the plunger supplied with a liberal coating of lubricating oil so as not only to lubricate the plunger and prevent it from rusting and thereby cutting out or 70 abrading the stuffing box packing, but also to prevent corrosion or pitting of the plunger. This feature of preventing pitting is most important, since not only does pitting tend in time to allow water to enter the 85 plunger and thereby render the elevator inoperative, but where a series of pits become grouped circumferentially about the plunger as frequently happens, the latter is greatly weakened at that point, and is very 90 liable to fracture, which of course would lead to a serious accident.

My invention is clearly shown in the accompanying drawing in which an elevator car 1 is carried upon one end of a plunger 2 95 which is adapted to reciprocate in a cylinder 3 under the action of fluid pressure. Fluid buffers 4, 4, are located at the bottom of the hatchway, and serve the purpose of limiting the travel of the car in a downward direction and also to stop the car without shock or jar in case of overrun. The usual controlling valve and counterweight for the car have been omitted from the drawings, for the purpose of simplicity 100 of illustration, but it is to be understood that the same would be arranged and used 105 in the customary manner.

The elevator of Fig. 1 is of comparatively great height and length of plunger and the latter may well be supported or guided at two points intermediate the car and cylinder. The upper follower 6 is supported and moved through the cables 7, 7, each of which is secured to the top of the hatchway and leads under a sheave 8 carried by the follower. From here the cable 7 leads up over a sheave 9 carried by the car and is made fast to the follower at the point 10. The lower follower 6 is suspended from and operated by a pair of cables 11, 11, each of which is secured to the top of the hatchway and leads under a sheave 12 carried by the lower follower. From here the cable leads up to the upper follower 6 and made fast thereto at the point 13. By reason of this arrangement of sheaves and cables, it is obvious that the upper follower of Fig. 1 will move with the car at $\frac{2}{3}$ rd car speed, whereas the lower follower will in like manner move with the car only at $\frac{1}{3}$ rd car speed. By reason of this arrangement the plunger will always be guided and supported by the followers 6, 6, at two points which are equidistant from each other and from the cylinder and car, respectively, regardless of the length of the plunger which protrudes from the plunger cylinder. When the car is at the lowermost floor landing, the followers 6, 6, are close together, and when the car is at the uppermost floor landing, the followers are automatically spaced apart as shown. The buffers 4, 4, prevent the car from approaching too close to the cylinder stuffing box and also prevent the car from settling on the followers.

In Figs. 2 and 3, the elevator travel is not so great as that of Fig. 1, and consequently but one follower is necessary or desirable. In this case the ratio of travel of car and plunger follower is 2:1, and the follower will automatically take up a position midway between the car and cylinder. This 2:1 movement of the follower is obtained by the system of roping shown which comprises a pair of cables 14, 14, which are secured to the top of the hatchway, and each cable leads down around the sheave 8 carried by the follower and is connected to the bottom of the car. Guide sheaves 15, 15, may be secured under the car to guide the cable 14, so that the follower will tend to hang with its axis coinciding with that of the plunger.

Referring to Figs. 4, 5, and 6, it will be seen that the follower 6 is made in two similar halves 16, 16, which are bolted together in position on the plunger 2 by bolts 17. The outward end of each half 16, 16 is slotted vertically and receives the tongue or shank 18 of a guide shoe 19 which latter is preferably lined with strips of hard wood or bearing metal as shown in Fig. 5. The

follower is lined with Babbitt metal or similar anti-friction bearing material 20 which may be formed by pouring in the usual manner and which is of considerably larger internal diameter than the diameter of the plunger, so as to leave a substantial clearance therebetween, the upper and lower ends being chamfered off as shown. An oil reservoir 21 is formed in each half of the follower which may be filled with oil by removing the screw plug 22. A tube 23 containing a wick leads from the upper part of each reservoir to a groove 24 formed in the bearing 20, and oil is conducted from the reservoir by means of capillary attraction. If desired, the tube 23 may be cut off so as to permit the oil to flow to the bearing by gravity. Surrounding the plunger at the bottom of the follower is a cup shaped member 25 of leather, felt, or other flexible material containing a series of incisions (see Fig. 4) which are in light contact with the surface of the plunger and serve uniformly to distribute the oil fed from the reservoirs 21, 21, over the surface of the plunger. The cup shaped member 25 may be secured to the follower in any desired manner but is here shown as being retained by a metal ring 26 which is screwed to the follower, the metal and member 25 being made in two pieces split on line with the two halves of the plunger follower.

A plunger follower constructed in accordance with my invention may easily be placed in position or removed merely by removing the bolts which hold the guide shoes 19 in position, whereupon the latter may be raised or lowered so as to permit the two parts 16, 16, of the follower to be disconnected from each other and removed. Since substantially all elevator plungers are in most cases of the same diameter, the follower may be used in substantially all installations, and when the distance between guide rails differs in different installations, it is merely necessary to supply guide shoes having different lengths of shanks 18 to enable the same structure to have universal use. The shanks 18 of the guide shoes may be provided with oval or elongated bolt holes so as to permit of a slight adjustment in their respective supporting members 16, 16, and thereby take care of any variation in the distance between the guide rails of different installations. The use of two independent reservoirs for feeding oil is a good feature for in case one should become empty through neglect or otherwise fail to feed oil, the other one may be depended upon to do the work. The follower embodies in a unitary structure a means for guiding and supporting an elevator plunger against lateral displacement and for preventing any swaying or see-sawing motion and at the same time maintains the plunger amply supplied

with lubricating material, and hence many of the disadvantageous features inherent in a plunger elevator are done away with.

Whereas Fig. 1 shows but two plunger followers, it is to be understood that in some cases I may use more than two followers depending largely upon the length and construction of the elevator plunger and the load that it has to carry.

While I have disclosed a preferred embodiment of my invention, I desire not to be limited to the precise arrangement of parts herein shown and described, since it is obvious that one skilled in the art could readily make changes and modifications therein without departing from the spirit and scope of my invention.

What I claim is:—

1. The combination with a plunger elevator, of a traveling guide for the plunger, and means associated with said guide for lubricating the plunger.

2. The combination with a plunger elevator, of a guide for the plunger, automatic means for causing said guide to travel with the car at a lesser speed than that of the car, and means associated with said guide for lubricating said plunger.

3. The combination with a plunger elevator, of a guide for the plunger, automatic

means for causing said guide to travel with the car at a lesser speed than that of the car, an oil reservoir carried by said guide, and means for conducting oil from the reservoir to the surface of the plunger.

35

4. The combination with a plunger elevator, of a guide for the plunger, automatic means for causing said guide to travel with the car at a lesser speed than that of the car, an oil reservoir carried by said guide, means for conducting oil from said reservoir to the plunger, and means for distributing the oil upon the surface of the plunger.

5. The combination with a plunger elevator, of guide rails therefor, a guide for the plunger comprised of two similar parts bolted together, the plane of division between the parts lying in a vertical direction, and guide shoes secured to each of said parts coacting with said guide rails, said shoes being detachable from said guide when the guide is in operative position.

In testimony whereof I have signed my name to this specification in the presence of two subscribing witnesses.

GUY B. SMITH.
